LIGHTING FIXTURE

Arnold Janowitz, 241 W. 23rd St.,
New York, N.Y.

Filed July 14, 1967, Ser. No. 7,799

Term of patent 7 years

Int. Cl. D26—02

U.S. Cl. D48—20

FIG.1

FIG.2

FIG. 1 is an elevation of a lighting fixture formed of teardrop-shaped components; and

FIG. 2 is a fragmentary side elevational view thereof. Both sides, front and rear, are substantially alike.

What I claim is:

The ornamental design for a lighting fixture, as shown and described.
